UNITED STATES PATENT OFFICE

2,643,070

CABINET FOR DISPENSING SHEET MATERIAL

Frank L. Broeren, Neenah, Archie S. Kruger, Green Bay, and Vincent C. Jones, Appleton, Wis., assignors to Marathon Corporation, Rothschild, Wis., a corporation of Wisconsin

Application June 5, 1951, Serial No. 229,976

2 Claims. (Cl. 242—55.5)

1

This invention relates to a cabinet for dispensing sheet material such as, wrapping paper, waxed paper, paper toweling, cellophane, foil, etc., from a supply roll.

It is an object of this invention to provide a cabinet from which the sheet material can readily be withdrawn and severed in any chosen length. It is another object of this invention to provide a cabinet wherein the sheet material will always be available for easy grasping. It is still a further object to provide a cabinet which may be used either when supported on a horizontal surface or on a vertical surface, and more particularly, a cabinet in which new rolls may be placed when the cabinet is supported on a vertical surface without the roll falling out of the cabinet. Other objects and advantages of the invention will be evident from the following description and accompanying drawings wherein:

Figure 1 is a perspective view of the dispensing cabinet,

Figure 2 is a rear elevation of the cabinet,

Figure 3 is a perspective view of the cabinet of Figure 1 showing the cover in open position and the roll removed,

Figure 4 is a side elevation of the cabinet showing parts broken away,

Figure 5 is a fragmentary perspective view of the cabinet showing one of the bearings for supporting the roll,

Figure 6 is a front elevation, partly in section, of the supply roll,

Figure 7 is a section taken along the line 7—7 of Figure 1, and

Figure 8 is a side elevation of the cabinet showing the cover open of the dispensing cabinet supported on a vertical wall.

The dispensing cabinet 1 is preferably made of metal and comprises a base 2 and cover 3. The cover is hinged by pivots 4 and 4' to the base. A passageway 5 between the front portion 6 of the cover 3 and a guide 7 extending along the front edge of the base 2 allows the sheet material within the cabinet to be withdrawn when the cover is closed as shown in Figures 1, 4 and 7.

The cover 3 includes two side walls 10 and 11 and convexly curved top wall 12. The front edge of the top wall 12 is preferably provided with serrations to form a serrated cutting edge

2

13. The cutting edge 13 is also preferably turned upward, as shown in Figure 4, so that the serrations will not mark the sheet material as it is being withdrawn.

5 The base 2 includes a bottom wall 15, and side walls 16 and 17, front wall 18 and rear wall 19. Extensions 20 and 21 integral with the side wall serve as brackets to carry at their ends the pivots 4 and 4' for supporting the cover. Front wall 18 carries guide 7 at the top thereof and in the embodiment shown guide 7 is an extension integral with the front wall 18. The leading portion 22 of the guide is convexly curved, the center portion 23 generally flat and lying in a plane generally parallel with the base, and the trailing portion 24 generally flat and parallel to the front portion 6 of the cover wall. The side walls 16 and 17 have inwardly offset portions 16' and 17' which are shaped to form partial bearings 25 and 26 for rotatably supporting the supply roll 29.

20 The supply roll 29 comprises sheet material 30, such as waxed paper, wound on a hollow core 31 which may be made of paperboard. In each 25 end of the core a metal flanged sleeve 32 is provided comprising a short sleeve 33 secured by projections 34, as shown for one end in Figure 6, to the core 31 and a circular axial flange 35 projecting beyond the end of the core.

25 The supply roll 29 of continuous sheet material is placed in the dispensing cabinet by disposing the flanges 35 of the flanged sleeves 32 on each 30 end of the roll in the bearings 25 and 26. It is a feature of this invention that these bearings 35 are partial bearings which are so positioned as to have portions 36 and 36' of the arcs thereof extend beyond the vertical axis of the roll to support the flanges 35 by gravity so that they remain in place when the cabinet is supported 35 on a vertical surface. (See Figure 8.)

40 To further insure that the roll remains in the bearings a boss 37 associated with bearing 25 extends within the flange 35 whereby the flange is secured against transverse movement between 45 boss 37 and the bearing 25. (See Figure 5.) The boss 37 is preferably formed from a strip of metal 38 welded to offset wall 16' and has a pair of U-shaped portions 39 and 39' which are adapted to fit over the bearing 25 and the flange 50 35. Only one bearing is provided with the boss

since the flange 35 must be inserted axially into this bearing when the roll is placed in the cabinet.

When a roll of sheet material, as for example, waxed paper, has been placed within the cabinet and the flanges 35 at each end thereof are resting on bearings 25 and 26, the free end of the web is drawn over guide 7 and the cover 3 is swung over the base 2 to close the cabinet. A latch 40 which cooperates with a keeper 41 is provided to retain the cover in closed position. The keeper 41 is a slot formed in an offset flange 42 on the rear wall 19. The latch 40, made preferably of a resilient strip of metal, is secured to the inside cover as by rivets 43 and is provided with a dent 44 at its end and a button-like protuberance 45 at its center. Associated with the latch 40 is a protuberance 46 on the cover 3 which serves to facilitate the lifting of the cover when unlatched. This protuberance is preferably formed from a portion of the cover to provide an opening 47 through which button 45 is accessible for releasing the latch 40 by pressing the button.

After the cabinet is locked closed, sheet material may be withdrawn from the cabinet and severed in any desired length by tearing along the serrated edge 13. A brake member 50 is provided to prevent the supply roll from unwinding too freely and also to prevent a tendency for the roll to roll back after the paper has been torn so that the free leading edge of the web is drawn back into the cabinet where it cannot be grasped. The brake member 50 is preferably formed of a resilient spring finger 51 secured to the inside cover of the cabinet by a bracket 52 as by welding and is positioned and arranged so that its free end frictionally engages the outer surface of the flange 35. The brake member 50 also serves to retain the roll in the bearings. Though obviously a brake may be provided at each end of the roll it has been found that only one located at the bearing not having the boss 37 will serve the two purposes. The simplicity of construction and the dual function of the brake member is a marked improvement over the art, such as U. S. 2,434,194.

Even though the roll is braked as described, the leading edge of the paper upon standing may tend to withdraw into the cabinet due to a tendency for the outer layer of the web to pull back off the roll. To overcome this tendency grippers 55 and 56 are provided which are adapted to engage the paper as it crosses guide 7. These grippers are formed of resilient spring metal fingers which are secured to the inside of the cover at 57 and 58 as by welding. The fingers are positioned and arranged so that their free ends frictionally engage the web as it overlies or moves over the guide 7. (See Figures 4 and 7.) Although two grippers are shown any suitable number may be provided to effect braking without interfering with the ease of withdrawing the web.

When the dispenser is used for dispensing waxed paper, which is inherently slippery, it is difficult to grasp the web only from the underside as in the dispenser shown in the aforementioned U. S. Patent 2,434,194. To facilitate grasping the web, a cut out area 60 is provided in the guide 7 immediately above which, and in alignment with, is provided an opening 61 in the curved top wall 12 of the cover. By this arrangement a person may easily grasp the web between his fingers and then withdraw the sheet material

The opening in the cover may extend through the edge 13 but it is preferred to have an uninterrupted and rigid cutting edge as shown for purposes of uniform tearing.

5 Rigidity of the serrated cutting edge 13 is further enhanced because it is turned upwardly as previously described. Additional rigidity is also obtained by an indentation 62 in front portion 6 of the cover since the stiff edges of the 10 indentation reduce flexing of the cover. This indentation 62 further serves to receive a suitable label 63 for the dispenser which, because of the indentation, cannot be accidentally brushed off.

15 When the dispensing cabinet is to be used on a table top or other horizontal support, it rests on rubber feet 65. When it is hung on a wall 66, it may be hooked through openings 67 by hooks 68 in the bottom wall 15 of the base 2.

20 When a roll is in the cabinet and the cover latched, sheet material may be withdrawn by grasping that portion of the free end of the sheet material exposed in the opening 71 between the fingers and pulling out as much material as desired. (See Figure 7.) The amount withdrawn can then be severed by tearing the withdrawn portion along serrated edge 13. (Figure 1.) After the desired material has been severed, another portion of the material will be exposed in opening 71 because of the operation of brake member 50 and grippers 55 and 56. Hence, material can readily be removed from the cabinet without further manipulation until the roll is exhausted.

35 To insert a new roll, whether the cabinet is vertically or horizontally supported, the button 45 of latch 40 is depressed and the cover swung open by grasping the protuberance 46. With the cover open the brake member 50 is moved out of contact with flange 35 resting in bearing 26 and hence the flange at this end of the roll may be lifted out of the bearing. The flange resting in bearing 25 may now be withdrawn axially. The new roll is placed in the bearings 25 and 26 in the reverse order, that is, flange 35 on one end of the roll is axially inserted in bearing 25 around boss 37, and the flange at the other end is laid in bearing 26. Sufficient material is unrolled so that the free end overlies the guide 7. The 40 cover is now swung closed and the latch 40 will automatically lock. The grippers 55 and 56 will engage the free end of the material and the brake member 50 will hold the end of the roll resting in bearing 26 in place. The cabinet is again ready 45 for use as described above.

50 The specific construction herein described is given as an illustrative embodiment of the invention and it is to be understood that other modifications and changes are intended to be included within the scope of the appended claims.

55 We claim:

1. A cabinet for dispensing sheet material from a roll wound on a hollow core provided with a flanged sleeve secured to each end of said core 60 comprising a base having opposed side walls, a cover having a cutting edge, a guide carried by said base disposed beneath said cover, said guide having a cut out area and said cover having an opening immediately above the cut out area of 65 said guide whereby the sheet material overlying said guide may be grasped, resilient fingers mounted on the inside surface of said cover positioned and arranged to frictionally engage sheet material overlying said guide, a partial 70 bearing formed in one side wall adapted to re-

ceive a flanged sleeve provided at one end of said hollow core and a boss secured to said side wall adjacent said bearing in a position whereby said flanged sleeve is retained in said bearing between said boss and said bearing, a second partial bearing disposed in the other side wall adapted to receive a flanged sleeve carried by the other end of said hollow core and a brake member associated with said bearing adapted to frictionally engage said sleeve and to retain said flanged sleeve in said bearing.

2. A cabinet for dispensing sheet material from a web wound on a hollow core provided with a flanged sleeve secured to each end of said core as defined in claim 1 wherein the partial bearings are arcuate in contour and extend beyond the vertical axis of the roll supported thereby.
